US00D983887S

(12) **United States Design Patent** (10) **Patent No.:** **US D983,887 S**
(45) **Date of Patent:** **** Apr. 18, 2023**

(54) **ACCESSORY FOR BUBBLE MACHINE**

(71) Applicants: **Dongsheng Shi**, Shenzhen (CN);
Xiangyi Chen, Shenzhen (CN)

(72) Inventors: **Dongsheng Shi**, Shenzhen (CN);
Xiangyi Chen, Shenzhen (CN)

(**) Term: **15 Years**

(21) Appl. No.: **29/786,402**

(22) Filed: **May 31, 2021**

(51) LOC (14) Cl. **21-01**

(52) U.S. Cl.

USPC **D21/401**

(58) **Field of Classification Search**

USPC D21/401, 402, 570, 572, 573; 446/15-21

CPC A63H 33/28

(57) **CLAIM**

The ornamental design for an accessory for bubble machine, as shown and described.

DESCRIPTION

FIG. 1 is a front, right, and top perspective view of an accessory for bubble machine showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the accessory for bubble machine that form no part of the claimed design.

1 Claim, 7 Drawing Sheets
